UNITED STATES PATENT OFFICE

2,411,319

SAFETY TONGS

Joseph Rudolph Duarte, Honolulu, Territory of Hawaii

Application September 7, 1945, Serial No. 614,894

1 Claim. (Cl. 294—104)

1

My invention relates to mechanics' tools and has for an object to provide a pair of tongs for handling electrified or hot elements with safety.

Another object of this invention is to provide automatically actuated tongs.

A further object of the invention is to provide a pair of tongs having an adjustable or removable jaw member.

A still further object of my invention is to provide a pair of tongs the handle of which is of insulation material.

Another object of the invention is to provide a pair of tongs the jaws of which are provided with an insulation coat.

Other features and advantages will become more readily apparent from the following description and the accompanying illustrative drawing in which:

Figure 1 is a longitudinal sectional view of my tongs,

Figure 2 is a detail view of an insulator handle, Figure 3 is an end view of Figure 2, and

Figure 4 is a section on line 4—4 of Figure 1.

In the accompanying drawing as above enumerated and in the following specification, like characters of reference indicate like parts throughout and in which 10, indicates my invention, which comprises an insulated handle 11, having bores 12 and 13, extending longitudinally there-through with a terminal enlarged recess 14, pivoted within which recess is a trigger extension 15, of a jaw 16, pressing against the wall 17, of the trigger is a cap 18, actuated by a spring 19, held in bore 13, by means of an insulator cap 20. The action of the spring upon the trigger is to hold the jaw 16, into engagement

2

with a jaw 21, the shank 22, of which is held in the bore 12, by means of a set screw 23. The shank 22, may be adjusted to extend the jaw 21, if necessary. The jaws 16 and 21, as illustrated are provided with respective teeth 24 and 25, which teeth may be of any desired formation. The jaws 16 and 21, as well as the trigger 15, may if so desired be provided with an insulating coating on the surfaces 26 and 27.

10 From the foregoing description it will be obvious that my safety tongs may be used either for electrical or heated work from which elements the operator or user of the tool will be protected from either shock or heat as the case may be.

15 It is thought that persons skilled in the art to which the invention relates will be able to obtain a clear understanding of the invention after considering the description in connection with the drawing. Therefore, a more lengthy description is regarded as unnecessary.

20 Changes in shape, size and rearrangement of details and parts such as come within the purview of the invention claimed may be resorted to, in actual practice, if desired.

25 Having now described my invention that which I claim as new and desire to procure by Letters Patent is:

30 A pair of tongs comprising a slideable jaw, a pivoted jaw, an insulator handle for the jaws, said handle having a bore through which the first jaw operates, said pivoted jaw being spring actuated and manually controlled, said pivoted jaw having a trigger depending from the handle for said manual control, and a longitudinal bore in the handle in which the spring is seated.

JOSEPH RUDOLPH DUARTE.
